(57) **CLAIM**

The ornamental design for a heated cat house, as shown and described.

DESCRIPTION

FIG. 1 is a top, front perspective view of a heated cat house, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front perspective view showing the heated cat house, in state of use; and,

FIG. 9 is a top, front perspective view showing the heated cat house, in another state of use.

All the broken lines in the drawings depict portions of the heated cat house that form no part of the claimed design.

1 Claim, 7 Drawing Sheets
